To all whom it may concern:

Be it known that I, Kay Bojesen, a subject of the Kingdom of Denmark, residing at Copenhagen, Denmark, have invented a new, original, and ornamental Design for a Wooden Toy Chassis, of which the following is a specification, reference being had to the accompanying drawing, forming part thereof, wherein the figure is a perspective view of a wooden toy chassis showing my new design, the opposite side presenting

The characteristic feature of my design resides in the fact that it can be adapted and used in conjunction with interchangeable parts to represent a truck or pleasure car.

I claim:
